UNITED STATES PATENT OFFICE

LOUIS BRENNER, OF NEW YORK, N. Y.

CARD CASE

Application filed May 24, 1932. Serial No. 613,308.

An object of the invention is to provide an inexpensive card case which has means to hold yieldingly the ends of cards contained in the card case, while permitting the convenient withdrawal of the cards from the card case as may be desired. The construction is such that, whether one or a number of cards is disposed between the covers, the card or cards will be held in position between the card case covers.

Another object of the invention is to provide a card case having a back with two spaced-apart covers extending from the back, with means for holding the covers adjacent the back yieldingly against cards disposed between the covers.

Still another object of the invention is to secure an elastic band to one of the covers, the elastic band normally extending around the other cover for pressing the covers in the direction of each other and against the cards disposed therebetween.

A further object of the invention is to provide the covers with grooves in their outer faces and recesses at the opposite edges of the covers which register with the grooves, the grooves and the recesses being provided for receiving the elastic band.

Additional objects of the invention will appear in the following specification in which the preferred form of the invention is described.

In the drawing similar reference characters refer to similar parts in all the views, of which

Figure 1 is a plan view of the card case, with parts broken away to illustrate the construction,

Figure 2 is a sectional view on the line 2-2 of Figure 1,

Figure 3 is a sectional view on the line 3-3 of Figure 1, with the elastic band disposed wholly at the outer side of one of the covers,

Figure 4 is a fragmentary view illustrating a modified form of the invention, and

Figure 5 is a sectional view on the line 5-5 of Figure 4.

By referring to the drawing it will be seen that the card case has a back 10 with

two covers 11 which are integral with the back 10 and which extend therefrom, one of the covers 11 being scored at 12 on a line parallel with the back 10 and the said cover having a groove 13 between the scored line 12 and the back 10, the groove 13 being disposed parallel with the back 10 and with a groove 14 in the outer face of the other cover 11. It will be seen by referring to Figures 1 and 3 that each of the covers 11 has recesses 15 in its opposite edges, the recesses 15 registering with the grooves 13 and 14.

Secured to one of the covers in its groove 14 there is an elastic band 16, the elastic band 16 being normally disposed around the two covers 11, as illustrated in Figure 2, and in the grooves 13 and 14 and the recesses 15 to press the covers 11 adjacent the back 10 in the direction of each other and for holding in position in the card case the cards 17 which are disposed between the covers 11.

It will be seen that, with this construction, an inexpensive card case is provided which may be used until the cards 17 are distributed, after which, if desired, another supply of cards may be introduced between the covers 11, or, if desired, the card case may be discarded and another card case filled with the cards 17 may be substituted. The cards 17 are held at their ends adjacent the back 10 by the pressure of the sides 11 under the influence of the elastic band 16 and one or more cards 17 may be readily withdrawn from between the covers 11 without displacing the remaining cards, the scoring 12 on one of the covers 11 permitting of the convenient raising of the said cover, so that the user may have ready access to the cards 17 for withdrawing the cards from the card case as may be desired.

The elastic band 16 will secure the cards 17 within the covers 11, not only when the card case is filled with cards, but also when practically all the cards have been removed, so that the last card may be held in place between the covers until it is withdrawn therefrom.

In the construction illustrated in Figures 1, 2 and 3, the elastic band 16 is secured in the groove 14 of one of the covers 11 by

stitches 18. The construction illustrated in Figures 4 and 5 is the same as that illustrated in Figures 1, 2 and 3, except that, in the construction illustrated in Figures 4 and 5, one of the covers 11 is cut along parallel lines 19 which are spaced apart and there is another cut 20 which connects the cuts 19 so that a flap 21 is provided, the elastic band 16 being disposed in the grooves 13 and 14 and under the flap 21, when a wafer 22 is disposed over the flap 21, the wafer extending beyond the flap 21 and being secured not only to the flap 21, but also to the cover 11 having the said flap. In other respects the form of the invention illustrated in Figures 4 and 5 corresponds with the form of the invention illustrated in the other figures.

What is claimed is:

- 20 1. A card case having a back and two covers spaced apart and extending from the back one of the covers being cut adjacent the back to form a flap, an elastic band disposed around the covers and under the flap, and means for holding the flap against the elastic band.
- 25 2. A card case having a back and two covers spaced apart and extending from the back, one of the covers having a transverse groove in its outer face approximately parallel with the back, the last mentioned cover being cut at the groove to form a flap extending from the cover, an elastic band disposed around the covers, the elastic band extending in the groove under the flap, and means for holding the flap against the elastic band.
- 30 3. A card case having a back and two covers spaced apart and extending from the back, one of the covers being scored on a line approximately parallel with the back, the covers having recesses in their edges adjacent the back, one of the covers having a transverse groove in its outer face approximately parallel with the back, the last mentioned cover being cut at the groove to form a flap extending from the cover, an elastic band disposed around the covers in the recesses and extending in the groove under
- 35 40 45 50 the flap, and means for holding the flap against the elastic band.

LOUIS BRENNER.
